CHANGE-OVER CARBURETOR

John R. Emerson, Flint, Mich., assignor to Borg-Warner Corporation, Chicago, Ill., a corporation of Illinois

Application August 23, 1941, Serial No. 408,028

3 Claims. (Cl. 261—18)

This invention relates to multiple fuel carburetors and particularly to an improved carburetor of this type for selectively feeding either a volatile fuel such as gasoline or a heavier fuel such as an oil or distillate.

It is an object to provide an improved arrangement responsive to manifold suction for selectively operating the valves controlling the supplies of the respective fuels. It is a more particular object to provide such an improved arrangement wherein there is no mechanical connection between the throttle valve assembly and the respective fuel supply valves. It is a still more detailed object to provide such an arrangement of means under the control of the throttle valve operable in accordance with the position of said valve for regulating the valve for regulating the vacuum control means in accordance with the position of the throttle, there being no mechanical connection between said throttle and said vacuum means.

It is another object to provide a novel manually controlled selective arrangement for either; (1) locking the vacuum responsive means in gasoline or volatile fuel supplying position; (2) for locking the vacuum responsive means in off or neutral position wherein neither gasoline nor distillate can be drawn into the carburetor; (3) for locking the vacuum responsive means in distillate supplying position; or (4) for releasing the locking means altogether, rendering the vacuum responsive means effective to operate either the gasoline supply valve or the distillate supply valve depending upon the degree of vacuum.

Still another object is the provision in an assembly of the present type of arrangement of means for preventing undesirable pulsations of the vacuum responsive means.

A further object is the provision of an improved arrangement of means for urging the vacuum responsive means in the direction opposite to that in which the same is moved in response to vacuum, this arrangement including an overcenter assembly.

Other and more specific objects, advantages and uses of my invention will become apparent from a reading of the following specification taken in connection with the accompanying drawings forming a part thereof and wherein:

Fig. 1 is a broken-away vertical section of a carburetor embodying the invention, taken generally along the axis of the main fuel and air mixing passage as indicated by the line 1—1 in Fig. 2;

Fig. 2 is a vertical cross-section taken substantially along the line 2—2 of Fig. 1 and showing to advantage the locking assembly as well as the overcenter assembly;

5 Fig. 3 is a horizontal section taken substantially along the line 3—3 of Fig. 1;

Fig. 4 is a vertical section through the distillate inlet and strainer assembly.

Fig. 5 is a broken-away vertical cross-section 10 taken substantially along the line 5—5 of Fig. 1 and showing to advantage the respective fuel inlet valves as well as the operating cam therefor;

Fig. 6 is a vertical cross-section taken substantially on the line 6—6 of Fig. 1 and showing to 15 advantage the manually controlled linkage for adjusting the locking assembly;

Fig. 7 is a horizontal axial section taken substantially on the line 7—7 of Fig. 1 and showing to advantage both the relation of the butterfly 20 throttle valve to the port controlling the vacuum responsive means as well as the relation of the throttle to the idle fuel supply ports:

Figs. 8, 9, and 10 are broken-away section 25 views showing the locking assembly in successive ones of the several selective positions into which the same is arranged to be moved. Fig. 8 shows the locking assembly in the position in which the vacuum responsive piston is locked in the lowered or distillate position; Fig. 9 shows

30 the locking assembly in the position in which the vacuum responsive piston is locked in the neutral or intermediate position wherein fuel cannot be delivered from either the distillate or the gasoline supply; while Fig. 10 shows the locking assembly in the position in which the vacuum responsive piston is locked in the raised or gasoline delivering position; and

35 Fig. 11 is a schematic broken-away vertical section with the essential parts shown in one 40 plane in order to present a more composite picture of the operation in a single figure of the drawings.

Referring in greater detail to the figures of the drawings 16 indicates generally a carburetor 45 assembly incorporating a preferred embodiment of my invention. A main housing or body 11 is formed with the usual main passage 12 therethrough having an air inlet 13 and a fuel and air outlet 14 adapted to communicate with the

50 manifold of an internal combustion engine (not shown). The flow through main passage 12 is under the control of the usual choke valve 16 and butterfly throttle valve 17, the fuel being introduced into main passage 12 through a nozzle 55 assembly indicated generally at 18 leading from

a fuel bowl 19 carried on the underside of main housing 11.

My invention is directed particularly to an improved arrangement indicated generally at 26 for selectively controlling the introduction into fuel bowl 19 of either a volatile gasoline or a heavy distillate fuel. This selection may be made manually or may be rendered completely automatic, that is, responsive to the position of throttle valve 17 which condition is selected because the same is an accurate index of the engine requirements for the respective fuels.

The selective fuel introducing assembly 26 includes a gasoline or other volatile fuel inlet 51 adapted to communicate with a suitable supply (not shown) and a distillate or other relatively less volatile fuel inlet 52 adapted to communicate with a suitable supply (not shown). Gasoline inlet 51 communicates through strainer assembly 53 with valve chamber 54 provided with valve seat 55 against which a valve 56 is normally maintained seated by compression coil spring 57. It will be noted that the main body portion of valve 56 is non-circular in cross-section permitting the ready flow of fuel therewith and to valve seat 55, conical valve portion proper 58 being arranged to engage valve seat 55 and having a coaxially extending operating pin portion 59 extending therefrom of lesser cross-sectional area than valve seat 55 and passing through said valve seat for engagement by the operating means as will appear. Valve chamber 54 is formed in a tubular member 61 externally and internally threaded for ready removal and ready replacement to facilitate cleaning and adjustment. Strainer assembly 53 includes a depending hollow housing 62 having a readily removable threaded plug 63 to permit of cleaning and containing a strainer cage 64 functioning to remove foreign particles from the fuel prior to delivery of the fuel to valve chamber 54.

Distillate inlet 52 communicates with an identical arrangement of elements designated 53a and 54a through 59a. Distillate outlet port 55a communicates with a chamber 71 while gasoline outlet port 55b communicates with a chamber 72, chamber 71 being in communication with chamber 72 through a coaxial passage 73 containing a floating reciprocable plunger 74 of non-circular cross-section permitting the ready flow of distillate from chamber 71 to chamber 72, the function of which plunger will be later described. For conducting fuel from chamber 72 to fuel bowl 19 passage 76 delivers to valve 77 under the control of float assembly 78 which functions to control the level of fuel in the fuel bowl 19.

Referring now to the arrangement for selectively controlling the operation of gasoline valve 56 and distillate valve 56a, cylinder 81 formed in an auxiliary housing section 82 carried on the upper portion of main housing 11 has mounted therein for reciprocation a vacuum responsive piston 83. This piston is normally urged in the direction of the lowermost position thereof by compression coil spring 84 and is further arranged to be placed in communication with main air and fuel passage 12 through a vacuum control port 85. This control port 85 communicates the pressure or vacuum existing within fuel and air passage 12 to the upper end of piston 83 through passage 86 in main housing 11, passage 87 defined between main housing 11 and auxiliary housing 82, vibration dampener chamber 88

and passage 89 leading to the upper portion of chamber 81.

Special attention is directed to the relationship between butterfly valve 17 and vacuum control port 85, it being noted that this port is under the control of the peripheral portion of the butterfly valve. Referring especially to Fig 7, it will be seen that the usual two-hole idle port arrangement indicated at 90 and 90a is under 10 the control of a first peripheral portion of butterfly valve 17 while vacuum port 85 is under the control of a second peripheral portion of this valve 17.

It will thus be seen that when the throttle 17 approaches idle position, namely, a position in the arcuate movement thereof just prior to passing over port 90a in the closing direction, the same will then be at the point of transferring port 85 from the low suction existing on the 20 nozzle side of throttle valve 17 to the higher manifold suction being built up on the manifold side of throttle 17. The port 85 is so located that the transition from exposure to relatively low to relatively high suction is made at a position 25 of the throttle at which the engine is normally operating at a speed slightly lower than fast idling or governed idling speed. When the port 85 is brought into the influence of high suction 30 by the passage of the throttle periphery thereby beyond in the closing direction, the resulting high depression or vacuum will be transmitted through passages 86, 87, vibration dampener chamber 88, and passage 89 to the upper end of piston 83 with the result that the piston is drawn 35 upwardly against compression spring 84.

The raising of piston 83 by the vacuum under the above described conditions is taken advantage of to accomplish the closing of distillate valve 56a shutting off the supply of the heavier 40 fuel to the fuel bowl as well as accomplishing the opening of the gasoline or more volatile fuel valve 56 thus admitting the latter fuel to fuel bowl 19. In this manner the engine supplied by carburetor 10 is made to operate on heavy distillate during part as well as full throttle, while 45 being furnished with a more volatile fuel during slow idling and up to, but not including fast or governed idling, under which condition it has been found that distillate alone will not effect 50 satisfactory idling of the engine.

To effect this selective operation of the gasoline valve 56 and the distillate valve 56a by piston 83, link 96 extends from the lower portion of piston 83 to which it is universally connected and terminates in a stop or end portion 97 cooperating with 55 a stop 98 formed on housing 11 for limiting the inward or downward movement of piston 83 by compression spring 84, whenever throttle valve 17 is moved in an opening direction to a sufficient 60 arcuate extent to expose vacuum port 85 to the pressure existing on the nozzle side of the throttle. A crank assembly indicated generally at 101 includes a first end portion 102 pivoted to connector link 96 at 103 adjacent the lower end 65 thereof, pivot 103 being a moving pivot. The mid-portion of crank assembly 101 is in the form of a yoke 104 a first arm 105 of which is drivably connected with a trunnion 106 journalled in bearing member 108. Also carried in bearing member 108 is a rotatable shaft 109 having a slotted 70 driving connection with trunnion 107 at one end and a driving connection at the other end thereof with a cam or crank member 111 formed with a cam surface 111a for cooperation with actuating pin 59a of valve 56a and formed with the cam

surface 111b for cooperation with the actuating pin 59 of gasoline valve 56. Bearing member 108 is in the form of a readily removable externally threaded hollow plug having a shoulder under the head thereof adapted to tightly engage a sealing ring for preventing leakage therewith. Shaft 109 is formed with a conical portion 112 for engaging the outer open end of bearing member 108 to effect a seat therewith. Extending from the outer end of shaft 109 is a coaxial pin 113 arranged to be engaged by a spherical bearing or ball 114 urged into engagement with the pin by compression spring 116 for effectively maintaining the sealed relationship between conical portion 112 and the outer end of bearing member 108. Cam or crank member 111 is mounted upon pin 113 and is arranged to be reciprocated by crank arm 117. The second yoke arm 106a has a second trunnion 107a extending therefrom and journalled in housing 11.

It will thus be seen that movement of piston 83 upwardly by the action of vacuum thereon will produce arcuate movement of crank assembly 101 trunnion 107 and cam 111 to move the latter into engagement with floating pin or plunger 74 which in turn engages pin 59 to move gasoline valve 56 into the open position causing the flow of gasoline into chamber 72, through passage 76 and float control valve 77, the quantity of flow being determined by float assembly 78. Reduction in the vacuum acting upon piston 83 will result in compression spring 84 effecting the lowering of piston 83 to bring the end 97 of link 96 into engagement with stop 98 turning crank assembly 101 in the opposite arcuate direction thus causing crank or cam arm 111 to move cam surface 111b out of engagement with trunnion 74 thus permitting the gasoline valve 56 to close under the influence of compression spring 57 and then bringing cam surface 111a into engagement with operating pin 59a of distillate valve 56a opening this valve and permitting the flow of distillate into chamber 71, and through passage 73 along non-circular plunger 74, into chamber 72, through passage 76 and past float control valve 77 into float bowl 19.

Insuring and facilitating the movement of the piston 83 and connecting links 96 in both directions beyond that position wherein crank or lever assembly 101 is disposed with the general axis thereof at substantially a right angle to the normal axis of link 96, there is provided a special over-center spring arrangement including spring 121 one end of which is connected to a fixed pivot indicated at 122 and the other end of which is connected to pivot 103 forming the connection between link 96 and crank assembly 101. It will be seen that the maximum stretch in spring 121 takes place when crank assembly 101 has the general axis thereof turned substantially into a horizontal plane on either side of which position spring 121 tends to contract with the result that there is less tendency for piston 83 to flutter and permit cam member 111 to assume a middle position between valves 56 and 56a.

Under certain conditions of operation it is desirable to lock valve operating assembly 26 selectively in either a distillate feeding position or a gasoline feeding position while under the condition where the motor is not operating it is equally desirable to lock the assembly against the inadvertent opening of either the distillate valve or the gasoline valve. To this end crank assembly 101 includes an extended terminal portion 131 formed with an arcuate mouth 132 arranged for

cooperation with a pin 133 carried by a locking cam designated generally at 134. Referring particularly to Figures 2 and 8 through 10 it will be seen that locking cam 134 may be moved to any one of four selected positions, including a first position shown in Fig. 8 wherein pin 133 is completely withdrawn from cooperation with arcuate mouth 132 thus permitting control entirely by vacuum responsive piston 83. Spring operated pawl 136 engages a detent in cam member 134 corresponding to each of the several positions for maintaining the cam in any position to which the same is moved by manual means to be described. The position of the locking cam assembly shown in Fig. 8 is the normal position of operation under conditions wherein the associated engine has been brought up to normal operating temperature and wherein there is an ample supply of both distillate and gasoline.

There are however certain conditions under which it is desirable to lock the valve control assembly in a completely off-position such as illustrated in Fig. 9 wherein locking cam assembly 134 has been moved to a position where spring operated pawl 136 engages position number 2, in which position locking pin 133 is moved approximately mid-way along arcuate mouth 132 to locked piston 83 in the mid position thereof wherein cam or crank member 111 is held in substantially the vertical plane and wherein the same does not engage either operating pin 59a of distillate valve 56a or plunger 74 which operates pin 59 of valve 56. In this position the compression springs 57 and 57a are effective to prevent the flow of either distillate or gasoline to fuel bowl 19. While assembly 26 is locked in such intermediate positions neither fuel can be inadvertently fed to the fuel bowl and any operation that may be desired in connection with the fuel bowl may be carried out, such for example as the removal of the plug 141 for the purpose of cleaning or adjusting the nozzle assembly 18.

Similarly it may be desired under certain conditions, such for example, as when starting a cold motor, to lock the valve control assembly 26 in gasoline supply position as illustrated in Fig. 10. Under such conditions cam assembly 134 is moved to a position where spring urged pawl member 136 is in engagement with the detent corresponding to position 1, locking pin 133 being moved completely within arcuate mouth 132 wherein it is effective to hold crank assembly 101 in a manner to restrain piston 83 in the lowermost position thereof irrespective of the degree of vacuum to which port 85 may be subjected.

The above described locking arrangement may have still further advantages and application such for example as under conditions wherein one or the other of the fuel supplies has become exhausted making it desirable to prevent attempted operation on the exhausted fuel and limiting the operation to that fuel which remains.

For the purpose of manually setting locking cam assembly 134 in any one of the several positions which may be selected I employ an assembly of linkage including a rotatable shaft 151 adapted to connect with a manually operated member (not shown) which is preferably located in the cab of the vehicle with which the carburetor is adapted to be associated. Shaft 151 operates crank 152 which in turn effects the arcuate movement of crank 153 through link 154, crank 153 being connected to shaft 156 support-

ing cam locking assembly 134. Thus by manually adjusting a control member (not shown) locking assembly 134 may be readily adjusted from any selected remote point.

It has been found in the operation of this particular type of change-over carburetor that there is a tendency under certain conditions of operation for the piston 83 to vibrate or be unsteady particularly during transition from one fuel to another or in other words, when the throttle valve 17 is being operated in the area of port 85. In order to overcome this tendency, I have provided, in addition to the above described novel arrangement of over-center spring 121 and compression spring 84, an improved arrangement of vibration dampening discs indicated at 157 contained in chamber 88. A plurality of these discs are employed, each comprising a thin sheet metal cup-like shape provided with a depending surrounding wall portion 158 fitting snugly within the peripheral wall of chamber 88 and each having a central opening or port 159 therein through which the depression from port 85 is transmitted to the upper end of piston 83. These discs 157 cause a certain amount of resistance to the change in flow through the ports formed therein with the result that a very decided dampening action is imposed upon any tendency of the piston to oscillate or flutter.

In addition to the above described structure, there is provided the usual necessary additional carburetor elements of a well-known character not forming a particular part of the present invention and not thought necessary of descriptions herein, such elements including the load adjustment assembly indicated generally at 161 and the necessary control linkage indicated generally at 162 for operating throttle valve 17. Rod 162 would generally be the governor rod, the governor (not shown) in turn being manually controlled by the operator for speeds under the established governed speed.

While my invention has been disclosed in connection with certain specific embodiments thereof, it is my intention that these be considered by way of example and not by way of limitation, my invention being defined by the appended claims which should be given a scope as broad as commensurate with the prior art.

I claim:

1. In a carburetor assembly for selectively delivering either a first relatively volatile fuel or a second less volatile fuel, including means defining a housing having a main passage therethrough with an air inlet thereto and a fuel and air outlet therefrom adapted to communicate with the manifold of an internal combustion engine, means defining a fuel bowl and float controlled valve for maintaining a predetermined level of fuel therein, means defining a nozzle assembly for delivering fuel from said bowl to said passage intermediate of said inlet and outlet portions thereof, a butterfly throttle valve positioned in said main passage between said nozzle and said outlet for controlling the flow therethrough, a first valve assembly adapted to control the flow of said first relatively volatile fuel to said bowl, a second valve assembly adapted to control the flow of said second less volatile fuel to said bowl, said arrangement being particularly characterized by the provision of means responsive to manifold vacuum in the area of said outlet for selectively operating said first and second valve assemblies, said means comprising a vacuum-

responsive piston and cam assembly, movement of said piston in the direction of one limit of movement being effective to cause said cam to operate one of said valve assemblies while the 5 movement of said piston in the direction of the other limit of movement thereof being effective to cause said cam to operate said other valve assembly, said arrangement including further a port formed in said housing in communication 10 with said main passage adjacent a peripheral portion of said butterfly valve when in or near closed position, means forming a passage for communicating said port with said vacuum-responsive piston, whereby the operation of said 15 throttle valve to substantially closed position corresponding to idle speed of an associated internal combustion engine results in the movement of said peripheral portion of said throttle over said port exposing the same to the relatively higher 20 vacuum existing at the outlet side of said throttle to thus effect the operation of said first valve assembly to deliver said relatively volatile fuel to said fuel bowl, while reverse movement of said throttle is effective to expose said port to the relatively higher pressure existing on the 25 nozzle side of said throttle valve thus effecting the operation of said second valve assembly to deliver said second less volatile fuel to said fuel bowl, said piston and cam assembly including a 30 depending rod or link universally connected at one end to said piston and formed at the other extremity as a stop member for limiting the inward movement of said piston, compression spring means for normally urging said piston in 35 a direction to cause the engagement of said stop, a crank assembly pivotally connected to said link intermediate the ends thereof and drivingly associated with said valve assembly operating cam, the raising and lowering of said piston being 40 effective to operate said cam through said crank assembly, and a tension coil spring having a first end connected to a fixed pivot on said housing and the other extremity thereof fastened to said pivotal connection between said link and 45 said crank in a manner such that the maximum stretch of said coil spring occurs at an intermediate position of the movement of said piston and link, the extreme positions of said piston corresponding to the minimum stretch in said 50 spring to thus assure the movement of said piston past said intermediate position in either direction.

2. In a carburetor assembly for selectively delivering either a first relatively volatile fuel or a second less volatile fuel, including means defining a housing having a main passage therethrough with an air inlet thereto and a fuel and air outlet therefrom adapted to communicate with the manifold of an internal combustion engine, means defining a fuel bowl and float controlled valve for maintaining a predetermined level of fuel therein, means defining a nozzle assembly for delivering fuel from said bowl to said passage intermediate of said inlet and outlet portions thereof, a butterfly throttle valve positioned in said main passage between said nozzle and said outlet for controlling the flow therethrough, a first valve assembly adapted to control the flow of said first relatively volatile fuel to said bowl, a second valve assembly adapted to control the flow of said second less volatile fuel to said bowl, said arrangement being particularly characterized by the provision of means responsive to manifold vacuum in the area of said outlet for selectively operating said first and second valve assemblies,

said means comprising a vacuum-responsive piston and cam assembly, movement of said piston in the direction of one limit of movement being effective to cause said cam to operate one of said valve assemblies while the movement of said piston in the direction of the other limit of movement thereof being effective to cause said cam to operate said other valve assembly, said arrangement including further a port formed in said housing in communication with said main passage adjacent a peripheral portion of said butterfly valve when in or near closed position, means forming a passage for communicating said port with said vacuum-responsive piston, whereby the operation of said throttle valve to substantially closed position corresponding to idle speed of an associated internal combustion engine results in the movement of said peripheral portion of said throttle over said port exposing the same to the relatively higher vacuum existing at the outlet side of said throttle to thus effect the operation of said first valve assembly to deliver said relatively volatile fuel to said fuel bowl, while reverse movement of said throttle is effective to expose said port to the relatively higher pressure existing on the nozzle side of said throttle valve thus effecting the operating of said second valve assembly to deliver said second less volatile fuel to said fuel bowl, said piston and cam assembly comprising a link or piston rod depending from said piston having a universal connection with said piston at a first extremity thereof, the other extremity functioning as a limit of movement stop for said piston in the inward direction, a rotatable driving assembly for said cam including a trunnion having a stationary bearing in said housing, a crank assembly drivingly associated with said trunnion intermediate the ends thereof, a first end portion of said crank assembly being pivotally connected with said piston rod intermediate the ends thereof to be driven by said piston, the other end portion of said crank assembly being formed with an arcuate mouth portion, and manually adjustable locking means for cooperation with said arcuate mouth in a plurality of positions for moving said crank assembly and said piston to either of the limits of movement thereof or to an intermediate position and holding the same in such selected position.

3. In a carburetor assembly for selectively delivering either a first relatively volatile fuel or a second less volatile fuel, including means defining a housing having a main passage therethrough with an air inlet thereto and a fuel and air outlet therefrom adapted to communicate

with the manifold of an internal combustion engine, means defining a fuel bowl and float controlled valve for maintaining a predetermined level of fuel therein, means defining a nozzle assembly for delivering fuel from said bowl to said passage intermediate of said inlet and outlet portions thereof, a butterfly throttle valve positioned in said main passage between said nozzle and said outlet for controlling the flow therethrough, 5 a first valve assembly adapted to control the flow of said first relatively volatile fuel to said bowl, a second valve assembly adapted to control the flow of said second less volatile fuel to said bowl, said arrangement being particularly characterized by the provision of means responsive to manifold vacuum in the area of said outlet for selectively operating said first and second valve assemblies, said means comprising a vacuum-responsive piston and cam assembly, movement of 10 said piston in the direction of one limit of movement being effective to cause said cam to operate one of said valve assemblies while the movement of said piston in the direction of the other limit of movement thereof being effective to cause said cam to operate said other valve assembly, said arrangement including further a port formed in said housing in communication with said main passage adjacent a peripheral portion of said butterfly valve when in or near closed position, means forming a passage for communicating said port with said vacuum-responsive piston, whereby the operation of said throttle valve to substantially closed position corresponding to idle speed of an associated internal combustion engine results in the movement of said peripheral portion of said throttle over said port exposing the same to the relatively higher vacuum existing at the outlet side of said throttle to thus effect the operation of said first valve assembly to 15 deliver said relatively volatile fuel to said fuel bowl, and means for dampening the movement of said vacuum-responsive piston, said means comprising a generally cylindrical chamber in communication at a first portion with said piston and in communication at a second portion with said vacuum control port, a plurality of superimposed cup-like discs received in said cylindrical chamber with the peripheral portions thereof in engagement with the surrounding wall of said chamber, each of said discs being formed with a perforation therethrough of limited size effective to communicate the changes of vacuum to said piston, said plurality of discs functioning to dampen said changes in the vacuum effects 20 transmitted from said port to said piston.

JOHN R. EMERSON.
